DEVICE FOR PRODUCING AEROSOLS

Lyle D. Goodhue, Berwyn, Md., assignor to
United States of America as represented by
Claude R. Wickard, Secretary of Agriculture,
and his successors in office

Application December 8, 1943, Serial No. 513,400

4 Claims. (Cl. 299—95)

(Granted under the act of March 3, 1883, as
amended April 30, 1928; 370 O. G. 757)

1

This application is made under the act of March 3, 1883, as amended by the act of April 30, 1928 and the invention herein described and claimed if patented, may be manufactured and used by or for the Government of the United States of America for governmental purposes without the payment to me of any royalty thereon.

In United States Patent No. 2,321,023, it is disclosed that parasiticidal aerosols can easily and conveniently be prepared by releasing to the atmosphere solutions of certain materials in liquefied gases held under pressure. An object of this invention is to provide an improved device for discharging aerosols.

The device of my invention is illustrated in the accompanying drawing, in which:

Figure 1 is an elevational view; and

Figure 2 is a section along the line 2—2 of Figure 1.

Referring with more particularity to the drawing, the numeral 11 designates the casing of the container formed of two sections 12 and 13, welded together at 14, a dip tube 15 extending from the exterior of the container through the top and terminating at a point near the bottom within the container. The liquid 16 within the container comprises a solution of a non-volatile parasiticide dissolved in a gas under pressure and may be any of the compositions hereinabove mentioned. The outer end of the dip tube is provided with a seal 17 of a material such as a soft metal or an alloy, above which there is secured to the casing of the container a small cylindrical shell 18, threaded on the inside. A plug 19, threaded on the outside, is adapted to engage the threads of the cylindrical shell 18. A conical shaped penetrator 20 is secured to the lower end of the plug 19 to contact and break the seal 17 when screwed down. Finger grips 21 are provided on the plug 19 to facilitate this operation. A small hole or capillary 22 (preferably about 0.020 of an inch in diameter) is disposed longitudinally through the plug 19. A short piece of tubing 23 is removably disposed between the bottom of the plug 19 and the tube 15 to prevent accidental puncturing of the seal 17 before initial use. When it is desired to use the device, the plug 19 is first taken out and the tubing 23 removed. The plug 19 is then replaced and screwed down until the seal is broken by the penetrator. The plug 19 is then retracted to permit escape of the liquid in the container through the hole 22. When it is desired to shut off this flow, the plug 19 is again screwed down to seat the penetrator 20 in the opening previously made by it in puncturing the seal 17. With this arrangement, the container may be shipped after being filled with the liquid under seal and without danger of leakage. Furthermore, when placed in the hands of the user, dispersion of the liquid can be controlled by simply manipulating the plug

19. Suitable resinous or other anti-leakage materials may be applied to the threads between the cylindrical shell 18 and the plug 19 to make the device operate more efficiently.

Having thus described my invention, I claim:

1. In combination, a hermetically sealed container, a dip tube extending from the exterior to the interior of the container, a tubular member about the opening of the dip tube on the outside of and integral with the container, a plug threadedly engageable with said tubular member, a yieldable seal in said dip tube, and a solid penetrator attached to said plug for rupturing said yieldable seal, said plug having an escape hole longitudinally therethrough, the lower end of said hole being radially offset from and non-contactable with that area of said seal which is rupturable by said penetrator.

2. In combination, a hermetically sealed container, a dip tube extending from the exterior to the interior of the container, a tubular member about the opening of the dip tube on the outside of and integral with the container, a plug threadedly engaged with said tubular member, a yieldable seal in said dip tube, and a solid penetrator attached to said plug for rupturing said yieldable seal and forming a seat therein for said penetrator, said seat and penetrator comprising a valve, said plug having an escape hole longitudinally therethrough, the lower end of said hole being radially offset from and non-contactable with said seat.

3. In combination, a hermetically sealed container, a dip tube extending from the exterior to the interior of the container, a tubular member about the opening of the dip tube on the outside of and integral with the container, a plug threadedly engageable with said tubular member, a yieldable seal in said dip tube, and a solid penetrator attached to said plug for rupturing a portion of said yieldable seal and thereby forming a seat therein for said penetrator, said seat and penetrator comprising a valve, said plug having an escape hole longitudinal therethrough, the lower end of said hole being radially offset from and non-contactable with said portion.

4. In combination, a hermetically sealed container, a dip tube extending from the exterior to the interior of the container, a tubular member about the opening of the dip tube on the outside of and integral with the container, a plug threadedly engageable with said tubular member, a yieldable seal in said dip tube, and a solid penetrator attached to said plug for rupturing a portion of said yieldable seal and thereby forming a seat therein for said penetrator, said seat and penetrator comprising a valve, said plug having an escape hole longitudinal therethrough, the lower end of said hole being radially offset from and non-contactable with said portion, and a removable spacer between said plug and said seal.

LYLE D. GOODHUE.
